UNITED STATES PATENT OFFICE.

CALVIN E. GRILL, OF SAN FRANCISCO, CALIFORNIA.

AUTOMATIC GUN.

Application filed June 30, 1924. Serial No. 723,203.

This invention relates particularly to an improved automatic gun.

An object of the invention is to provide a gun having a mechanism therein which will automatically extract a discharged cartridge from the gun barrel, cock the cartridge firing pin, and insert a loaded cartridge into the gun barrel, in one complete cycle of operation.

10 A further object of the invention is to provide an automatic action for guns wherein the cartridge supply mechanism to the gun barrel is mechanically controlled and operated in unison with the breech block.

15 Other objects of the invention relate to an improved breech block and shell extractor, and to the mechanism for operating the same, and also to a gun action that is superior in point of simplicity, inexpensiveness 20 of construction, positiveness of operation, and facility and convenience in use and general efficiency.

In this specification and the annexed drawings, the invention is illustrated in the 25 form considered to be the best, but it is to be understood that the invention is not limited to such form, because it may be embodied in other forms, and it is also to be understood that in and by the claims following the description, it is desired to cover the invention in whatsoever form it may be embodied.

In the accompanying three sheets of drawings,

30 Fig. 1 represents a side elevation of a gun constructed in accordance with my invention.

Fig. 2 is an enlarged side elevation, partly broken away, of Fig. 1 showing the cartridge supply conduit.

40 Fig. 3 is a vertical section through the gun showing the breech block and its component parts in the cocking position.

Fig. 4 is a fragmentary side elevation of Fig. 1.

45 Fig. 5 is a plan view of Fig. 4 partly broken away.

Fig. 6 is a plan section taken through Fig. 3 on the line 6—6.

50 Fig. 7 is a side elevation of the latch mechanism holding the barrel and butt stock together.

Fig. 8 is a plan section taken through Fig. 3, on the line 8—8.

Fig. 9 is a cross-section taken through Fig. 3, on the line 9—9. 55

Fig. 10 is a cross-section taken through Fig. 3, on the line 10—10.

Fig. 11 is a vertical section through the breech block on the line 12—12 of Fig. 5. 60

Fig. 12 is an end view of Fig. 11. 65

Fig. 13 is a perspective view of a portion of the breech block showing the shell extractor removed.

Fig. 14 is a perspective view of the shell extractor. 70

Fig. 15 is a perspective view of the shell ejector.

Fig. 16 is a plan view of the intake in the cartridge receiver.

Fig. 17 is a fragmentary detail view of 75 the supply conduit within the butt stock together with the spring and follower.

In detail the construction illustrated in the drawings comprises a gun barrel 1 of any desirable length and calibre, on an end of which a receiver or housing 2 is fixedly mounted. The receiver 2 is provided with a cartridge intake 3 on one side thereof and a shell discharge port 4 on the opposite side. 80 A cartridge firing mechanism consisting of the breech block 5 and its component parts is reciprocatingly arranged in the said receiver in axial alignment with the barrel 1. The barrel 1 and receiver 2 are formed for the purpose hereinafter set forth, substantially an integral unit. The rear part of the receiver 2 is provided with a wall 6 thereon which is adapted to engage a pin 7 fixed on the rear end of the butt stock 8, and a notched pin 9 is mounted on the forepart of 85 the barrel 1 which is adapted to engage a latch 10 on the butt stock 8. The latch 10 is automatically held in engagement with the pin 9 by means of an expansion spring 11,— 90 a control rod 12 being secured to the latch 10 so that the said latch may be manually disengaged from the pin 9. Although I have shown and described one particular form of mechanism by which the gun barrel and butt stock may be held in detachable engagement, 95 it is to be understood that any equivalent form of attaching mechanism might be substituted in lieu thereof.

A cartridge magazine or supply conduit 13, consisting of a hollowed metal tube, is 100 mounted within the butt stock 8 and ex- 105

tends from a point adjacent the shoulder rest 14 up to a point in registering communication with the cartridge intake 3 in the receiver 2. The cartridges are supplied to 5 the cartridge conduit, bullet end foremost, and are moved toward the discharge end of said conduit by means of an expansion spring 15 confined within a follower tube 16. The follower 16 is adapted to be passed into 10 the magazine 13 to force the cartridges out of the opposite end of the said magazine. The bottom end of the spring 15 rests against a plug stop 17. The stop 17 has a cam face on one end thereof, and said cam face abuts 15 against the end edge of a notched latch 18 pivoted at 19 in the end of the follower tube 16. The notched edge of the latch 18 is moved by the expansion spring 15 and cam action between the stop 7 and latch 18, into 20 engagement with the butt stock to hold the spring 15 in the cartridge magazine in position to eject cartridges therefrom.

A breech block 5 is reciprocatingly arranged in the receiver 2 and said breech 25 block is adapted to move axially with respect to the barrel bore. The breech block is substantially cylindrical in cross-section, the larger end thereof forming a bearing surface to slide within the receiver, while 30 the reduced end 20 of the said breech block extends within the receiver to a point adjacent the inner end of the barrel 1. One end of the expansion spring 51 is confined in a hollow end 52 of the breech block 5, 35 the opposite end of said spring is arranged around a pin 53, secured in the wall 6, mounted on the end of the receiver 2. The spring 51 serves to check the recoil of the breech block 5, resulting after the discharge 40 of a cartridge, and to return said breech block to position for further firing operations. The interior of the breech block 5 is hollowed out to receive the body 22 of a firing pin. The firing pin 23 is an integral portion of the body 22 and extends 45 outwardly in a milled slot 24 provided in the exterior of the reduced end 20 of the breech block 5. The interior of the body 22 is slotted at 25 to receive the head end 50 26 of a connector 28 pivoted on a pin 27 held in the breech block 5. By swinging the connector member 28 on its pivot the end 26 thereof will engage an end of the firing pin body 22 and move the same rearwardly within 55 the breech block against the tension of an expansion spring 29. The opposite end of the spring 29 abuts against a stop member 30 held in the end of the breech block 5 by a pin 31 which has an end 32 projecting below the breech block 5, for the purpose to be hereinafter described. Swinging movement is imparted to the connector member 28 either, automatically, on the recoil of the breech block 5—when the free end 60 65 33 of the connector will slide over a cam

member 34 fixed in the butt stock 8, or, manually—when the breech block 5 would be pulled back by a cocking member 35 engaging the projecting end 32 of the pin 31 and the connector 33 would ride over the 70 surface of the cam 34.

Irrespective of whether the breech block is moved back automatically by the recoil, or moved manually, the firing pin is cocked by swinging movement of the connector 28 75 70 engaging the cam 34. The body 22 of the firing pin is moved to the firing or cocked position by the end 26 of the connector 28 where it is engaged by the notched arm 36 of a sear 37, shaped as a bell crank. The sear 37 is pivoted at its elbow on a pin 38 held in the breech block 5. A flat spring 39 is mounted on the exterior of the breech block 5 to engage the sear 37 to force the notched end into engagement with the firing pin body 22 to hold the same in the cocked position. I do not depend upon the spring 39 to force the notched end of the sear 37 into engagement with the firing pin body, but have arranged the opposite arm 40 of the sear to contact with a cam face 41 on the connector 28 so that the said connector will engage the arm 40 of the sear to positively move the opposite notched end of the said sear into the desired engagement with the firing pin body 22. In order to release the firing pin from engagement with the sear I have provided a pin 42 which extends through the connector 28 and projects beyond both ends thereof. A compression spring 43 is mounted around the pin 42 within the connector 28. Thus by elevating the projecting lower end 44 of the pin 42 against the spring compression by means of the trigger 45, in the manner to be hereinafter described in detail, the upper end of the pin 42 would engage adjacent the notched end 36 of the sear 37 to elevate said sear away from the firing pin body member 22 to permit said firing pin to be moved forward by the expansion of the spring 29.

A portion of the periphery of the reduced end of the breech block 20 is squared off on 100 opposite sides to provide a central shoulder 46. The tubular body 47 of a shell extractor is fixed around the shaft 20 adjacent where it is joined to the breech block 5. A pair of fingers 48 and 49 are formed integrally on the extractor collar 47 and said fingers are 105 arranged on the reduced end of the breech block so that the finger 48 will lie in parallel registry with the squared shoulder 46, while the opposite extractor finger 49 will be positioned diametrically opposite. The extractor fingers 48 and 49 have an outward yieldable movement so that the notched ends thereof may be disengaged from a cartridge shell, by an ejector 50 which is adapted to 110 strip the fingers 48 and 49 from the said 115 120 125 130

shell. The ejector 50 is arranged within the receiver 2, so that the spaced walls 54 and 55 thereon will lie over and around the squared shoulder 46 and extractor finger 48 5 on the breech lock. The ejector 50 is positioned within the receiver 2 adjacent the discharge port 4 therein, so that the shells will be stripped from the breech block when the said breech block reaches the limit of its 10 rearward movement. The ejector 50 operates to engage one of the extractor fingers 48 to lift it away from the surface of the breech block with which it lies in contact, to release the hold which the extractor fingers 15 may have on the end of the cartridge shell.

A gate 56 is mounted in a slotted opening 57, adjacent the intake port 3 in the receiver 2, contiguous to the discharge end of the 20 shell magazine 13. The gate 56 is arranged so that an end 58 thereof will close off the discharge end of the shell magazine, and prevent a cartridge from being passed into the receiver, except at the proper interval. 25 A pin 59 is provided on the gate 58 to move a cartridge from the magazine 13 over into the receiver 2 to align with the bore of the barrel 1. The gate 56 is splined on a spirally grooved shaft 60 which is rotatably 30 journaled in bearings 61 and 62 provided in the butt stock. The spiral shaft 60 is connected by a rod 63 to a slotted plate 64 within which the end 32 of the breech rod pin 31 is confined. Movement of the breech 35 rod 5 and pin 31 will cause a corresponding movement of the spiral shaft 60, within predetermined limits according to the length of the groove in the plate 64, and in turn the gate 58 will be moved, in and out, relative 40 to the magazine discharge.

The invention operates in the following manner. In the initial operating position the breech block 5 lies against the inner end of the barrel 1, substantially as shown by 45 dotted lines in Fig. 2 and Fig. 5. In order to move a cartridge from the magazine into the firing chamber the handle 35 would be pulled rearwardly, which in turn would pull the breech block rearward as shown in Fig. 50 3. This movement of the breech block would, through the connected members, cause a corresponding rearward movement of the spiral shaft 60 which would throw the gate 56 away from the end of the magazine discharge and permit one cartridge 55 to be advanced ahead of the gate onto the pin 59 mounted thereon. Simultaneously with the movement of the magazine control gate by the breech block, the connector 28 60 would be pulled back into contact with the cocking cam 34 whereby the said firing pin body would be moved backward into engagement with the latching sear 37, as shown in Fig. 3. Upon the breech block 5 reaching 65 the extreme limit of its rearward move-

ment it would be advanced forwardly relative to the receiver by the expansion of the recoil spring 51—and as the said breech block moves forwardly, the end of the reduced portion of the breech block would 70 come into contact with the end of the cartridge ejected from the magazine to move the cartridge into the bore of the barrel, substantially as shown in Fig. 2. As the end of the breech block 5 moves the cartridge into the barrel bore the rim on the end of said shell is engaged by the fingers 48 and 49 of the extractor member. In the position shown in Fig. 2 the connector 28 lies in a substantially vertical position so that by pulling on the finger grip 63 on the trigger 45, said trigger would be elevated into contact with the end 44 of the pin 42 confined in the connector 28. The elevating movement of the trigger forces the pin 42 80 upwardly to disengage the sear 37 from the firing pin body 22. The firing pin then advances within the breech block and contacts with the end of the cartridge, to fire the said cartridge. The force of the explosion within the cartridge causes it to move rearwardly in the barrel with force sufficient to move the breech block rearwardly within the receiver and to cause the shell to be withdrawn from the barrel bore by the extractor fingers. The shell is stripped from the extractor by the ejector 50 and passed out the discharge port 4 in the said receiver 2. 90

The rearward movement of the breech block, after the firing of the cartridge, causes the gate over the cartridge magazine to be opened to move a charged cartridge into the firing chamber in the receiver—and simultaneously, the firing pin is cocked by the connector 28 which engages the cocking cam 34. The recoil spring 51 then moves the breech block 5 forward so that the end thereof engages the rim of the new cartridge, and the gate 56 is moved back over the end 105 of the magazine discharge to prevent the supply of shells from entering the firing chamber. The action of pulling the trigger fires the cartridge, discharges the cartridge shell from the firing chamber, and reloads 110 the gun for further operation—in unison with the firing pin being cocked for a second firing operation. The upward pull on the trigger by the finger of the operator places the trigger in an elevated position so that repeated firing of cartridges will not take place except after allowing the trigger to be dropped back into its lowermost position. In order to prevent more than one cartridge being fired by a single pull of 115 the trigger I have pivoted a spring latch 64 on a pin 65 within the butt stock. A curved ended pin 66 is slidably confined in the latch 64 and forced outwardly by the expansion spring 67 which is adapted to force the pin 120 125 130

66 against the upper edge of the trigger to force the said trigger 45 downwardly. The latch 64 is provided with a curved face 68 on one side thereof which engages a correspondingly curved face on the lower side of the connector 28. Thus after the breech block 5 has been moved against the recoil spring 51, and the firing pin has been cocked by the connector 28, the opposite end 33 of the said connector 28 moves into engagement with the curved face 68 of the latch 64. The latch 64 moves the end 33 of the connector 28 down on the trigger until the projecting pin 44, in the connector 28, engages a notch 69 on the trigger, against which it is held by the spring latch 64. As soon as the trigger is dropped by the finger of the operator, the pin on the connector disengages from the latch 69 and the trigger is in readiness to again elevate the connector pin 44 to again cause the firing pin to be released and to cause the cartridge in the gun barrel to be discharged. After completion of a firing operation and while the trigger is still held in an elevated position, and the cocking of the firing pin is completed by the connector, said connector moves back against the latch 64 and the pin 44 in the connector is advanced into contact with the notch 69 in the trigger against which it is held inoperative, until the trigger is dropped by the finger of the operator, when the connector and pin would be released and rendered operative, for further firing, by upward movement of the trigger.

Having thus described this invention, what I claim and desire to secure by Letters Patent is:—

1. In an automatic gun, the combination of a barrel; a cartridge receiver adjacent the end of said barrel; a breech block, movable axially relative to said barrel; a firing pin in said breech block; a sear pivoted in said breech block to engage said firing pin; a cam operated connector to cock said firing pin; means in said connector to release the sear and firing pin; and a trigger to actuate said means.

2. In an automatic gun, the combination of a barrel; a cartridge receiver adjacent the end of said barrel; a breech block, movable axially relative to said barrel; means to manually move said breech block; a firing pin in said breech block; a sear pivoted in said breech block to engage said firing pin; a cam operated connector to cock said firing pin; means in said connector to release the sear and firing pin; and a trigger to actuate said means.

3. In an automatic gun, the combination of a barrel; a cartridge receiver adjacent the end of said barrel; a breech block, movable axially relative to said barrel; a firing pin in said breech block; a sear pivoted in said breech block to engage said firing pin; a

cam operated connector to cock said firing pin; means in said connector to release the sear and firing pin; a latch interposed between the trigger and connector to render said connector inoperative; and a trigger to actuate said means.

4. In an automatic gun, the combination of a barrel; a cartridge receiver adjacent the end of said barrel; a breech block, movable axially relative to said barrel; means to manually move said breech block; a firing pin in said breech block; a sear pivoted in said breech block to engage said firing pin; a cam operated connector to cock said firing pin; means in said connector to release the sear and firing pin; a latch interposed between the trigger and connector to render said connector inoperative; and a trigger to actuate said means.

5. In a firearm, the combination of a barrel; a cartridge receiver having an intake and discharge ports therein adjacent one end of the barrel; a breech block; a firing pin in the breech block; a sear to hold the firing pin cocked; a connector to cock the firing pin and engage the sear therewith; means in the connector to disengage the sear from the firing pin; and a trigger to actuate said means.

6. In a firearm, the combination of a barrel; a cartridge receiver having an intake and discharge ports therein adjacent one end of the barrel; a breech block; means to manually move said breech block; a firing pin in the breech block; a sear to hold the firing pin cocked; a connector to cock the firing pin and engage the sear therewith; means in the connector to disengage the sear from the firing pin; and a trigger to actuate said means.

7. In a firearm, the combination of a barrel; a cartridge receiver having an intake and discharge ports therein adjacent one end of the barrel; a breech block; a firing pin in the breech block; a sear to hold the firing pin cocked; a connector to cock the firing pin and engage the sear therewith; means in the connector to disengage the sear from the firing pin; a spring latch interposed between said trigger and connector to render said connector inoperative and to depress said trigger; and a trigger to actuate said means.

8. In a firearm, the combination of a barrel; a cartridge receiver having an intake and discharge ports therein adjacent one end of the barrel; a breech block; means to manually move said breech block; a firing pin in the breech block; a sear to hold the firing pin cocked; a connector to cock the firing pin and engage the sear therewith; means in the connector to disengage the sear from the firing pin; a spring latch interposed between said trigger and connector to render said connector inoperative and to de-

press said trigger; and a trigger to actuate said means.

9. In an automatic gun, the combination of a barrel; a cartridge receiver adjacent the end of said barrel; a breech block, movable axially relative to said barrel; a spring to actuate the breech block; a firing pin in said breech block; a sear pivoted in said breech block to engage said firing pin; a cam operated connector to cock said firing pin; means in said connector to release the sear and firing pin; and a trigger to actuate said means.

10. In an automatic gun, the combination of a barrel; a cartridge receiver adjacent the end of said barrel; a breech block, movable axially relative to said barrel; means to manually move said breech block; a spring to actuate the breech block; a firing pin in said breech block; a sear pivoted in said breech block to engage said firing pin; a cam operated connector to cock said firing pin; means in said connector to release the sear and firing pin; and a trigger to actuate said means.

11. In an automatic gun, the combination of a barrel; a cartridge receiver adjacent the end of said barrel; a breech block, movable axially relative to said barrel; a spring to actuate the breech block; a firing pin in said breech block; a sear pivoted in said breech block to engage said firing pin; a cam operated connector to cock said firing pin; means in said connector to release the sear and firing pin; a spring latch interposed between said trigger and connector to render said connector inoperative; and a trigger to actuate said means.

12. In an automatic gun, the combination of a barrel; a cartridge receiver adjacent the end of said barrel; a breech block, movable axially relative to said barrel; means to manually move said breech block; a spring to actuate the breech block; a firing pin in said breech block; a sear pivoted in said breech block to engage said firing pin; a cam operated connector to cock said firing pin; a spring latch interposed between said trigger and connector to render said connector inoperative; and a trigger to actuate said means.

13. In a firearm the combination of a barrel; a cartridge receiver having intake and discharge ports therein adjacent an end of the barrel; a breech block movable axially in said receiver relative to said barrel; a spring to actuate the breech block; a firing pin reciprocatingly mounted in said breech block; a spring to actuate the firing pin; a connector to cock the firing pin through rearward movement of the breech block; a sear to hold the firing pin cocked; means in the connector to disengage the sear from the firing pin; and a trigger to actuate said means.

14. In a firearm the combination of a barrel; a cartridge receiver having intake and discharge ports therein adjacent an end of the barrel; a breech block movable axially in said receiver relative to said barrel; a spring to actuate the breech block; a firing pin reciprocatingly mounted in said breech block; a spring to actuate the firing pin; a connector to cock the firing pin through rearward movement of the breech block; means to manually move the breech block to cock the firing pin; sear to hold the firing pin cocked; means in the connector to disengage the sear from the firing pin; and a trigger to actuate said means.

15. In a firearm the combination of a barrel; a cartridge receiver having intake and discharge ports therein adjacent an end of the barrel; a breech block movable axially in said receiver relative to said barrel; a spring to actuate the breech block; a firing pin reciprocatingly mounted in said breech block; a spring to actuate the firing pin; a connector to cock the firing pin through rearward movement of the breech block; a sear to hold the firing pin cocked; means in the connector to disengage the sear from the firing pin; a latch interposed between said trigger and connector to render said connector inoperative; and a trigger to actuate said means.

16. In an automatic gun, a barrel, a receiver; a spring actuated breech block reciprocatable in said receiver; a spring actuated firing pin in said breech block; a firing pin cocking lever pivoted in said breech block; a sear to hold the firing pin cocked; a spring actuated rod in the cocking lever to release the sear from the firing pin; a trigger to actuate said rod; and means on the trigger to prevent continuous actuation of the firing pin rod when the trigger is in firing position.

17. In an automatic gun, a barrel, a receiver; a spring actuated breech block reciprocatable in said receiver; a spring actuated firing pin in said breech block; a firing pin cocking lever pivoted in said breech block; a sear to hold the firing pin cocked; a spring actuated rod in the cocking lever to release the sear from the firing pin; a trigger to elevate said rod into firing position; and means on the trigger to engage the firing pin rod after completion of a firing operation to prevent said firing pin rod being again elevated until the trigger is dropped from firing position.

18. In an automatic gun, a barrel, a receiver; a spring actuated breech block reciprocatable in said receiver; a spring actuated firing pin in said breech block; a firing pin cocking lever pivoted in said breech block; a sear to hold the firing pin cocked; a spring actuated rod in the cocking lever to release the sear from the firing pin;

a trigger, having a shouldered portion therein, to elevate said rod into firing position; a spring latch to engage the trigger to resist elevating movement thereof, and to force the 5 firing pin rod in the cocking lever against the shouldered trigger after completion of a firing operation to prevent said firing pin

rod being again elevated until the trigger is dropped from firing position.

In testimony whereof, I have hereunto set 10 my hand at San Francisco, California, this 12th day of June 1924.

CALVIN E. GRILL.
